FRANK T. SEIBERT, OF INGOMAR, PENNSYLVANIA, ASSIGNOR TO JONES & LAUGHLIN STEEL CORPORATION, OF PITTSBURGH, PENNSYLVANIA, A CORPORATION OF PENNSYLVANIA.

STOCK GUIDING AND FEEDING MECHANISM.

Application filed May 4, 1926. Serial No. 106,709.

The present invention relates to stock feeding mechanism or steady rests for metal working machines, and the invention aims generally to improve mechanisms for feeding and guiding the stock in various metal working machines where it is desirable to present a longitudinally moving and rotating cylindrical piece of work, such as shafting, to a finishing tool, as for instance a grinding and polishing wheel or the like, as shown and described in my copending application filed simultaneously herewith, Serial No. 106,710 filed May 4, 1926.

Further aims and advantages appear hereinafter in connection with the description of the embodiment of my invention selected for illustrative purposes and shown in the accompanying drawings, wherein

Fig. 1 is an elevation of a steady rest for a shafting grinding machine constructed in accordance with the present invention, parts thereof being shown in section better to show the construction;

Fig. 2 is a plan view thereof partly in section;

Fig. 3 is a vertical sectional view taken on the line 3—3 of Fig. 1; and

Figs. 4 and 5 are a detail end view and side elevation, respectively of one of the bearing blocks, showing the helical rib thereon adapted for engagement in a groove in the guide ways, and indicating the extent of angular twist due to changes in adjustment to suit different diameters of stock.

In the embodiment of the invention illustrated in the drawings, the base 10 supports a housing or support 11, preferably annular in shape, which is formed with radial pockets for guide ways 12. As shown in Fig. 1, the sides of the housing are preferably open at the centers to permit movement of the work 13 transversely therethrough.

For the purpose of guiding or feeding the work longitudinally, and simultaneously rotating it, I provide a plurality of rolls 14 journaled upon spindles 15 mounted in bearing blocks 16 which are slidably mounted within the housing 11 so as to be capable of movement radially in the guide ways 12. In the arrangement illustrated in the drawings, three rolls 14 are provided, which are equidistantly spaced around the axis of the

work. Preferably the upper roll is resiliently mounted so as to permit yielding of the roll due to slight irregularities in the work. In the embodiment of the invention shown in the drawings, the bearing block 16 of the upper roll is counter-bored to form an internal annular flange 17 adapted to engage over and be supported by an outwardly extending flange 18 on a thimble 19. A spring 20 is positioned within the bore of the upper portion of the bearing block, and surrounding the thimble 19, and is held under compression against the flange 17 by means of a nut 21 threaded upon the thimble, thereby resiliently pressing the assembled bearing block 16 and roll 14 inwardly and downwardly.

The assembled roll units are each supported adjustably within the guide ways 12 by means of shafts 22 each of which is secured at one end to the thimble 19, in the case of the upper roll or to the bearing block 16, in the case of the two lower rolls, by a pin 23 or other suitable means. At the opposite end of each, these shafts are threaded to cooperate with threaded sleeves 24, which are suitably supported in the peripheral wall of the housing 11 to permit rotation, preferably in unison, whereby rotation of the threaded sleeves 24 will effect simultaneous movement of the shafts radially.

For the purpose of simultaneously adjusting each of the rolls radially in the guide ways 12, I preferably secure to each of the sleeves 24 a pinion 25 adapted to mesh with a single ring gear 26 mounted to rotate in the peripheral wall of the housing 11. Suitable means is provided for rotating the ring gear 26, as for instance an adjusting pinion 27 secured upon a stub shaft 28 supported by the housing 11. The ring gear is preferably provided with a scale 29 adapted to cooperate with a pointer 34 to indicate the radial adjustments of the rolls (see Fig. 2). Preferably the scale 29 is so graduated as to indicate the diameters of the shafts for which the rolls are adjusted.

When the invention is embodied in a driven steady rest for the purpose of feeding the cylindrical work longitudinally, the angularly disposed rolls 14 are driven in any suitable manner, as by shafts 30, so as simulta-

neously to rotate and feed the work longitudinally. Reference is made to my application Ser. No. 106,710 filed May 4, 1926, referred to above, wherein means for rotating the rolls are illustrated.

My invention contemplates the provision of automatic means for angularly adjusting the rolls according to the diameter of the work for which they may be adjusted so as 10 to feed work of different diameters at approximately the same linear speed. According to the embodiment of the invention shown in the drawings, the bearing blocks and the guide ways 12 are formed with co-operating helically arranged guides for the purpose of twisting the bearing blocks to change the angular adjustment of the rolls when adjusted radially. As shown, a member 31 is securely attached to each side of 15 the bearing block 16, said member being formed with a helical rib 32 adapted to slide in a corresponding groove 33 in the adjacent guide plate 12. Thus it is obvious that as the rolls 14 (see Fig. 3) are adjusted 20 radially outward to accommodate work of larger diameters, the angular position or obliquity of the rolls with reference to the shaft will be decreased and vice versa (see Figs. 4 and 5). In Fig. 4 the lines A B and 25 A' B' indicate the relative angularity of the axes of the rolls to the axis of the stock X—X for two pieces of stock of different diameter, the setting for the larger being indicated by the lines A B and the smaller by A' B', the corresponding positions of the 30 rolls being shown in dotted lines. By reason of this construction, with the machine illustrated it is possible to feed cylindrical objects, such as shafts, of a wide range of sizes, as 35 for instance from 1 1/4 inches to 6 inches in diameter, at substantially the same rate and the same speed of rotation.

Advantages of the invention are its simplicity of construction, compactness of arrangement of parts, and ease with which the rolls may be adjusted to work of different 45 diameters. Furthermore by the simple and single adjustment of the rolls for the diameter of the work, the accurate angular adjustment of the rolls is simultaneously effected automatically, whereby to feed the work 50 at substantially the same linear speed.

Obviously my invention is not to be restricted to the details shown and described.

55 What I claim as new is:

1. Mechanism for feeding and rotating cylindrical work to a metal working machine comprising a support having radial guideways, roll assemblies mounted in said guideways, means for adjusting the roll assemblies radially to accommodate work of different diameters, said guideways and assemblies being formed with oppositely disposed mating helical members whereby the 60 angular position of the roll is changed with

reference to the axis of the work simultaneously and in accordance with the radial adjustment of the roll assembly.

2. Mechanism for longitudinally feeding and rotating cylindrical work comprising a 70 housing having radial guideways, bearing members mounted in said guideways, rolls journaled in said bearing members, means for driving said rolls, means for adjusting said bearing members and driven rolls radially to accommodate work of different diameters, said guideways and bearing members being formed with oppositely disposed mating helical members for changing the angular position of the roll with reference to the 75 axis of the shaft simultaneously and in accordance with the radial adjustment of the roll, and a single means rotatably supported upon said housing and having engagement with each of the adjusting means for the 80 bearing members whereby said bearing members may be simultaneously uniformly adjusted to accommodate work of different 85 diameters.

3. Mechanism for longitudinally feeding and rotating cylindrical work to a metal working machine comprising a housing having radial guideways, bearing members mounted in said ways, power driven rolls carried by said bearing members and means 90 for adjusting said bearing members radially in said ways comprising threaded shafts each secured at one end to a corresponding bearing member, rotatable means mounted in said housing and having threaded engagement with each of said shafts, and common means for rotating all of said rotatable means whereby each of the rolls is 95 simultaneously adjusted radially within the housing, said bearing members and guideways being formed with oppositely disposed mating helical members for changing the angular position of the rolls with reference to the axis of the work simultaneously and in accordance with the radial adjustments of the rolls.

4. In a feeding device for a shaft grinding machine of the character described, sets of feed rolls disposed in the same transverse plane and surrounding the axis of the shaft, means for rotating said feed rolls at the same speed from a common source, journals for said feed rolls, said journals being rotatably mounted in alining bearings on brackets carried by slides radially movable in fixed guides extending towards the axis of said shaft from a plurality of directions, said slides and guides being formed with oppositely disposed mating helical ribs and grooves for giving a twist to said brackets as they are adjusted radially toward or from said shaft, and screw means on said brackets for adjusting said brackets and feed rolls toward or from said shaft and securing them in adjusted position.

5. In a feeding device for a shaft grinding machine of the character described, sets of feed rolls disposed in the same transverse plane and surrounding the axis of the shaft, 5 means for rotating said feed rolls at the same speed from a common source, journals for said feed rolls, said journals being rotatably mounted in alining bearings on brackets carried by slides radially movable in fixed 10 guides extending towards the axis of said shaft from a plurality of directions, said slides and guides being formed with oppositely disposed mating helical ribs and grooves for giving a twist to said brackets as they are adjusted radially toward or 15 from said shaft, and screw means on said brackets for adjusting said brackets and feed rolls toward or from said shaft and securing them in adjusted position, said screw adjusting means comprising a common 20 operating means providing individual radial and angular adjustment of said brackets and rolls simultaneously.

In testimony whereof, I have signed my name to this specification.

FRANK T. SEIBERT.
